UNITED STATES PATENT OFFICE

MARSHALL T. SANDERS, OF WILMINGTON, DELAWARE, ASSIGNOR TO DARCO CORPORATION, OF WILMINGTON, DELAWARE, A CORPORATION OF DELAWARE

MEANS FOR ACTIVATING CARBON

Original application filed February 3, 1931, Serial No. 513,217. Divided and this application filed March 2, 1932. Serial No. 596,356.

This invention relates to means for activating carbon; and it comprises an apparatus for activating carbon including a heat insulated vertical reaction chamber of relatively large cross-sectional area provided with a tangential lateral extension of small diameter inclined at a small angle to the horizontal, with means for introducing into said extension air as a current and with means in 5 the extension for suspending and dispersing finely divided carbonaceous material in the introduced air current, said reaction chamber having a gas outlet at the top and means for removing activated carbon at the bottom 10 and being advantageously provided with a steam inlet adapted to effect in the chamber treatment with steam of the carbonaceous material after its ignition with air and after 15 its separation from the gases formed in said 20 ignition; all as more fully hereinafter set forth and as claimed.

Activation of carbonaceous materials to increase their power of adsorption is accomplished by heat treatment in various ways, 25 one of the commonest being the subjecting of raw material or of "spent" material during the heat treatment to an atmosphere of CO₂ or steam or products of combustion containing both. As a rule the temperatures maintained during such treatment have ranged well 30 above 800° C. and in some cases have been above 1,300° C. It has also been proposed to use air as an activating agent during the heat treatment with a view to applying the oxidizing 35 action of the air oxygen to prevent charing of the material and consequent clogging of its pores. When air has been thus used it has usually been found necessary to keep the temperature below 500° C. to prevent overburning and it has been found impossible under 40 these conditions to obtain a satisfactory degree of uniformity in the operation and product. The action of air at low temperatures is slow and hence the capacity of the 45 apparatus is limited. Temperature control is difficult.

Various apparatus arrangements have been used in activating carbon. Sometimes the material is treated in horizontal rotating 50 cylinders, sometimes in stationary vertical

chambers. The reaction chambers have been in some cases externally heated and in others they have been adapted to internal heating by superheated activating gases. Combinations of both internal and external heating 55 have been proposed.

In the patent to Davis No. 1,873,998, whereon the present invention in some of its aspects is an improvement, a method of carbon activation, particularly adapted to revivification 60 of spent carbons, is described and claimed wherein activation is effected by the action of air at temperatures ranging around and above 800° C. in an externally heated tube, the amount of air being definitely proportioned to the amount of volatile matter in the 65 material undergoing activation and a selective oxidation of volatile matter or adsorbed matter being effected during passage of a carbon-air dispersion through the tube. 70

I have found that by means of a special arrangement of apparatus the activation of suitable raw material or the revivification of spent activated carbon can be accomplished, 75 using air oxygen as the activating agent and obtaining all of the heat needed to maintain the activating temperature from the exothermic reaction of the oxygen upon the material being activated. So doing, I find it advantageous to control the temperature by conserving the heat of reaction through adequate insulation of the reaction chamber and by introducing a controlled quantity of steam 80 into the reaction chamber. It is also advantageous to adapt the reaction chamber to 85 effect therein a separation of the carbon material from the gaseous products produced by the air and to introduce steam into the reaction chamber at such a location that steam reacts with the carbon material after its separation from the air reaction gases. The steam acts both to complete the carbon activation and to moderate the temperature by endothermic action as well as by taking up 90 sensible heat.

In an apparatus embodiment of my invention, involving operation of the described method, the carbonaceous material to be activated is after fine grinding suspended and dispersed in a current of air passing through 100

a somewhat inclined chamber which delivers into a vertical chamber of substantially larger area than the inclined chamber and the steam is introduced into the vertical chamber advantageously at a point well below the point of entry of the carbon-air dispersion; the vertical chamber being provided with gas outlet at the top and with carbon outlet means at the bottom; the cross-sectional area of the vertical chamber being such that the activated carbon settles out of the gases to the bottom of the chamber.

In a modified form of my apparatus the vertical reaction chamber is divided into an external and an internal portion, the air reaction taking place in the external chamber and thereby heating the internal chamber and the carbon, after separation from the air gases, being transferred from the bottom of the external chamber to the top of the internal chamber to be dropped through an upward current of steam introduced near the bottom of the internal chamber.

In the process embodiment of my invention the oxidation by air oxygen of the material being activated is relied upon to maintain the temperature proper for speedy activation, which I have found to be from 800 to 1,050° C., a part of the heat of the exothermic oxidation being utilized in supplying the heat absorbed in the endothermic oxidation of the carbon material with steam. In some cases it is desirable to preheat the steam and for this the gases formed in the activation reactions may be used as fuel. The air also may be preheated.

Regulation of the operation of the present invention, using air alone as the activating agent, may be merely by dissipating the heat formed in the activating reaction as by externally cooling the reaction chamber. But in most cases I find it better to conserve the heat of reaction by carrying it on in a heat insulated chamber and introducing steam into the chamber in an amount so proportioned to that of the air that the temperature is moderated and controlled within the desired range. In all cases the quantity of air in which the starting material is dispersed is carefully regulated in proportion to the volatile matter in the material. The quantity of air varies with different materials and usually ranges between 70 and 130 cubic feet (measured at 60° F. and atmospheric pressure) per pound of volatile combustible matter in the raw material. In a properly insulated reaction chamber the necessary activating temperature can in most cases be maintained with a proportion of air to carbonaceous material such that CO is formed with but little CO₂, the heat being largely provided by selective oxidation of contained volatile combustible matter to CO and H₂O, but little of the solid carbon of the raw material being consumed. With greater air

ratios more CO₂ may be formed and some of the solid carbon may be gasified. When using a raw material such for example as lignite, the conditions of temperature, time or rate of reaction and air ratio can be so adjusted that high yields of finished activated carbon are obtained and the gases produced in activation have a good fuel value.

It is of course possible to use oxygen-enriched air in the present process and when oxygen for enrichment is cheaply available, this may have advantage in increasing apparatus capacities.

In the accompanying drawings I have shown more or less diagrammatically apparatus within my invention.

In this showing,

Fig. 1 is a view in vertical section of an activating apparatus;

Fig. 2 is a horizontal section along the line A—A of Fig. 1;

Fig. 3 shows a view in vertical section partly in elevation of an activating apparatus similar to that shown in Figs. 1 and 2 but having additional means for effecting the activation in two stages; a portion of the showing of Fig. 1 being omitted from Fig. 3.

Referring first to Figs. 1 and 2, the vertical activating chamber 10 is provided with a refractory lining 11 backed by heat insulating material 12 and has an external metal shell 13. The activating chamber has a tangential projection 14 inclined at a small angle to the horizontal, which is adapted to receive through a funnel 15 the finely powdered material to be activated. Funnel 15 is provided with a star valve 16 and receives the ground material from hopper 17. A worm and tube may be used instead of the funnel and valve for introducing carbon material into 14. Into the outer end of the lateral chamber 14 a current of air is blown (by suitable means not shown) through air conduit 18 provided with a meter 19. As shown, the inclined projection 14 joins with vertical chamber 10 near its middle portion and the vertical chamber has a cross-sectional area much larger than that of the projection, being thereby adapted to cause separation from the gases in the chamber of suspended material carried by the air current through the inclined lateral chamber. Vertical chamber 10 has a conical bottom 20 which is shown as un-insulated, and from the bottom leads a conduit 21 provided with a valve or worm 22, the arrangement being adapted for continuous removal of activated material from the activating chamber after its separation from the gases in the chamber. Gases leave the vertical chamber 10 through the stack 23 and removal of the gases may be assisted by a suitable suction device (not shown). Into the vertical chamber 10 at a level well below that of the lateral chamber 14 steam can be admitted through a steam

line 24 provided with a meter 25. The steam is advantageously admitted to chamber 10 in a tangential stream. The activating chamber is adapted to insertion of pyrometers at 5 26, 27 and 28 for purposes of temperature observation and control.

In operation, the activating chamber 10 is first brought to a suitable temperature, about 800° C., by combustion of gas therein or by 10 other suitable means and then finely divided carbonaceous material such as lignite, spent activating carbon, etc. is admitted through funnel 15 and suspended and dispersed in a current of air introduced through air conduit 18 and is blown through chamber 14 into the vertical chamber 10 where the mixture becomes ignited. I have found that the air volume required for satisfactory working 15 may be varied between 70 and 130 cubic feet 20 (measured at 60° F. and atmospheric pressure) per pound of volatile matter in the carbonaceous material. The best air ratio varies according to the nature of the material being activated, and to the temperature 25 and the rate of carbon-air feed. The air ratio can be readily determined by trial. I have obtained a highly activated carbon 30 from a lignite with an air ratio of about 70 cubic feet per pound of volatile combustible matter in the lignite as determined by the usual proximate analysis. The tangential 35 relation of chamber 14 to chamber 10 is advantageous and with a suitably regulated air draft the burning off of the volatile matter 40 from the carbonaceous material proceeds rapidly and regularly in chamber 10 and the chamber is held by the heat of the reaction itself at between 800° and 1100° C. In this 45 temperature range many carbonaceous materials have been found to be well activated in the short time during which they are treated in the vertical chamber and the activated material separates from the products of the air combustion in the vertical chamber 50 to settle in the conical bottom 20 and to be removed by means of the conduit 21 through the valve 22, the arrangement being such as to prevent gas from passing out of the chamber with the activated product. The reaction 55 temperature in chamber 10 is controlled by the introduction of steam through pipe 24 and the steam aids in the activation. This pipe advantageously delivers tangentially into chamber 10 and the material separating 60 from the gases in the upper part of chamber 10 is treated with steam in the lower part. The steam is introduced in the quantity necessary to hold the temperature inside chamber 10 at the desired point. H₂O contained 65 in the raw material tempers the heat developed by the air. If desired, a cooling chamber may be inserted between chamber 10 and outlet valve 22. Sometimes the flame produced by the ignited mixture in chamber 70 strikes back into projection 14 and igni-

tion may occur as the air and carbon mix. This usually does no harm and in some cases is of advantage in increasing the time of treatment but as a rule it is better to maintain a rate of air flow in 14 sufficient to prevent the flame striking back. It is found 70 advantageous to have chamber 14 considerably inclined with respect to the vertical chamber, without the inclined chamber being actually horizontal. Ordinarily the pressure in chamber 10 is kept slightly above atmospheric, a positive pressure around 0.1 inch water being in most cases satisfactory. Higher pressures or subatmospheric pressures can be applied if desired. 80

Certain materials require a more extended treatment with steam to effect a high degree of activity, and in such cases the apparatus shown in Fig. 3 may be used. In this apparatus an inner un-insulated metal tube 30 is placed in chamber 10, into which is introduced through side chamber 14 a current of air and dispersed carbon as in the apparatus of Fig. 1, the means for doing this being omitted from the showing of Fig. 3. The steam is admitted near the bottom of tube 30 through valved pipe 31 provided with meter 32. 85

Tube 30 is heated externally by the air activation reaction taking place in chamber 10 and the air treated material is withdrawn from chamber 10 through conduit 33 and valve 34 and is conveyed by conveyor 35 to the hopper 36, from which it is delivered through valve 37 into the top of tube 30. Activation of the material begun in chamber 10 is then completed by the steam treatment in tube 30 and the activated material is withdrawn from the tube through conveyor 38. Gases leave tube 30 through pipe 39 at 90 the top. The tube temperature is observed by means of a pyrometer inserted at 40. In the steam treatment the fine particles of material delivered into tube 30 by valve 37 are retarded in their fall by the upward current of steam and gaseous reaction products and the time of treatment is thereby extended. 95

In treating various materials to produce activated carbon some variations of method and means is sometimes desirable. For example, when working with a readily activatable material such as some of the spent activated carbons produced in decolorizing processes, it may be desirable to increase the rate of throughput and it may then be advantageous, as stated ante, to use an un-insulated chamber 10 and sometimes even to externally cool this chamber as by a water spray. So doing, a high rate of throughput 100 with a concomitant high rate of heat development and dissipation becomes possible without sacrifice of the degree of activity imparted to the product. 105

This application is a division of my prior 110

and copending application Serial No. 513,-
217, filed February 3, 1931.

What I claim is:—

1. Apparatus adapted for activating carbon by an exothermic reaction with air oxygen, said apparatus comprising in combination a vertical chamber provided with a heat insulating lining adapted to maintain within the chamber an activating temperature developed solely by the heat set free in the activating reaction, a heat insulated tangential lateral inclined projection on said chamber, means at the outer upper end of said projection for introducing thereinto a regulated current of air, regulated positive feed means arranged in said projection for dispersing pulverized carbon in said air current, a gas outlet near the top of the vertical chamber and positive means for continuous removal of activated carbon from the bottom of the chamber, said last-named means being sealed against passage of gas therethrough.
2. Apparatus for activating carbon comprising a vertical heat insulated chamber, an inclined tangential lateral projection on said chamber, means at the outer upper end of said projection for introducing thereinto a current of air, positive feed means in said projection for dispersing pulverized carbon in said air current, a steam inlet pipe in the vertical chamber at a level below that of the inclined projection, a gas outlet near the top of the vertical chamber and positive means for continuous removal of activated carbon near the bottom, said last-named means being sealed against passage of gas therethrough.
3. Apparatus for activating carbon comprising an outer heat-insulated vertical chamber, an inclined chamber in open communication with, and of less cross-sectional area than, the vertical chamber and projecting from the side of the vertical chamber at a small angle to the horizontal, said inclined chamber comprising means for introducing a mixture of air and finely-divided carbonaceous material into the vertical chamber, an outlet for gas at the top of the vertical chamber, means for removing partially activated carbon from the bottom of the vertical chamber, a vertical inner chamber located inside the outer vertical chamber and adapted to be heated by exothermic reactions taking place in the outer chamber, means for introducing partially activated carbon into the top of the inner chamber and means for removing activated carbon from the bottom thereof, an inlet for steam near the bottom of said inner chamber, and an outlet for gas near the top.
4. Apparatus for activating carbon by an exothermic oxidizing reaction, which comprises three chambers: an inner chamber having heat-conducting walls with an inlet and an outlet for gases and an inlet and an outlet for powdered carbon, an outer chamber surrounding the inner chamber but out of

direct communication therewith and having an outlet for gas and an outlet for powdered carbon, and a third chamber inclined to and opening directly into the outer chamber tangentially and providing an inlet for carbon and oxygen-carrying gas into said outer chamber; and means for transferring carbon from the outer chamber to the inner chamber.

5. Apparatus for activating carbon comprising a vertical refractory-lined chamber, a refractory-lined chamber of less cross-sectional area inclined at an angle to the vertical chamber, tangential to the chamber and in open communication therewith near its middle, positive gas-tight means for continuously introducing powdered carbon into the inclined chamber near the outer upper end thereof, positive gas-tight means for continuous withdrawal of carbon from the lower end of the vertical chamber, means for introducing air into the outer, upper end of the inclined chamber and means for introducing steam near the bottom of the vertical chamber, controlling means for each of said introducing means, and an outlet for gas at the top of the vertical chamber.

6. Apparatus for producing activated carbon comprising an outer heat insulated chamber provided with means for introduction therein of a current of air carrying admixed powdered carbonaceous material, said outer chamber having a gas outlet near the top and a gas-tight outlet for solid material at the bottom, an inner non-insulated chamber within said heat insulated chamber, out of communication therewith and adapted to be heated by heat transfer from the outer chamber, a gas inlet near the bottom of the inner chamber, and conveying means for transferring the solid material from said gas-tight outlet to the top of the inner chamber.

In testimony whereof, I have hereunto affixed my signature.
